INVENTOR

Edward H. Ashcroft,

Attorneys.

UNITED STATES PATENT OFFICE.

EDWARD H. ASHCROFT, OF BOSTON, MASSACHUSETTS.

IMPROVEMENT IN AUTOMATIC FIRE-EXTINGUISHERS.

Specification forming part of Letters Patent No. **144,493**, dated November 11, 1873; application filed October 30, 1873.

To all whom it may concern:

Be it known that I, EDWARD H. ASHCROFT, of Boston, in the county of Suffolk and State of Massachusetts, have invented certain new and useful Improvements in Automatic Fire-Extinguishers; and I do hereby declare the following to be a full, clear, and exact description of the invention, such as will enable others skilled in the art to which it pertains to make and use it, reference being had to the accompanying drawings, which form part of this specification.

My invention relates to a novel device for turning on water in stand-pipes by means of which fire may be extinguished. It contemplates an apparatus that will by the expansion of air, due to heat, automatically open the valve or valves in the water-pipe.

In the drawings, Figure 1 is a section and elevation of my improvement. Fig. 2 shows a variation in its application. Fig. 3 represents a gage and an air-pump for the purpose of testing the air-tightness of the tube.

The following is a description of my invention: A is a cylinder. B is a piston moving snugly therein. C is a shaft that operates the water-cock D, situated in the stand-pipe E. F is a pipe, closed in every part except as it opens into the cylinder A. This pipe is provided with a flange on its lower end, by which it can be secured to the top of the cylinder A; or it may be screwed or otherwise fastened thereon. The lower end of the cylinder A is provided with openings or air-vents *a*, and incloses the shaft C sufficiently tight to act merely as a guide.

The operation of the device is as follows: The pipe F is trained into any apartment of the building, or upon the outside of the building adjacent to any structure that in burning would endanger the building, and the other end of the pipe is carried down to a point adjacent to the water-pipe E, and there terminates in the cylinder A, which is inclosed so as to prevent persons from meddling with it. In case of a fire anywhere in the vicinity of the pipe F, the air within the pipe becomes

rarefied and expands, driving the piston B through the cylinder A, and the shaft C operates directly or indirectly to turn the stop-cock D in the water pipe E. The water will then rise through the pipe E, and be projected through perforations in the pipe upon the parts of the structure on fire or endangered.

In order that the pipe F may be readily tested as to its air-tightness, I propose to employ an air-pump, G, above the piston B and the gage H, and thereby, by exhausting the air from the pipe F, or compressing the air within the pipe F, the gage H will indicate its air-tightness. Several of these automatic devices may be attached to several water-pipes leading to the different apartments, so that the action of the air-pipe F in turning on the water will not flood apartments that are not endangered.

The devices shown in the drawings for turning on the water are intended only as examples of the many appliances that may be employed for that purpose.

Packing *f* should be properly placed between the joints wherever they occur. Perforations *a* are made in the bottom of the cylinder A, above the lowest point reached by the piston B, through which the excess of expanded air may find vent, and which also prevent the drawing back of the piston B, and consequently closing of the valve D, owing to a sudden cooling of the pipe F. In some instances, however, it might be desirable to have the water automatically turned off when the fire had become extinguished. If desired, a valve opening inward may be placed near the top of the cylinder A, so that suction due to a sudden cooling of the pipe F may not draw back the piston B, and thus shut off the water; or an arrangement of pawls and ratchets may be made so that the expansion would open the water-valve; but in drawing back, the pawl would ride over the ratchets and not act to close the said valve.

Having thus described my invention, what

I claim as new, and desire to secure by Letters Patent, is—

1. The combination of the cylinder A, closed pipe F, piston B, and shaft C, for automatically operating a valve, D, substantially as described and set forth.
2. The cylinder A, provided with the perforations *a a*, in combination with the pipe F and piston B.
3. The combination of cylinder A, pipe F,

piston B, pump G, and gage H, substantially as described.

In testimony that I claim the foregoing I have hereunto set my hand this 29th day of October, 1873.

EDWARD H. ASHCROFT.
